CLAIM

The ornamental design for a backside cover, as shown and described.

DESCRIPTION

FIG. 1 is a rear perspective view of a backside cover, as worn by a person, according to a first embodiment of the present invention;

FIG. 2 is an enlarged rear perspective view of the backside cover, as worn by a person, of FIG. 1;

FIG. 3 is a rear view of the backside cover, of FIG. 1;

FIG. 4 is a left side view of the backside cover of FIG. 3;

FIG. 5 is a right side view of the backside cover of FIG. 3;

FIG. 6 is a front view of the backside cover of FIG. 3;

FIG. 7 is a top view of the backside cover of FIG. 3;

FIG. 8 is a bottom view of the backside cover of FIG. 3;

FIG. 9 is a rear perspective view of a backside cover, as worn by a person, according to a second embodiment of the present invention;

FIG. 10 is an enlarged rear perspective view of the backside cover, as worn by a person, of FIG. 9;

FIG. 11 is a rear view of the backside cover of FIG. 9;

FIG. 12 is a left side view of the backside cover of FIG. 11;

FIG. 13 is a right side view of the backside cover of FIG. 11;

FIG. 14 is a front view of the backside cover of FIG. 11;

FIG. 15 is a top view of the backside cover of FIG. 11; and,

FIG. 16 is a bottom view of the backside cover of FIG. 11.

The broken lines showing a human wearing the backside cover are environmental and form no part of the claimed design. The broken lines showing portions of the backside cover form no part of the claimed design.

1 Claim, 8 Drawing Sheets
